PAPER BOX CONSTRUCTION

Charles A. Stopper, Camden, N. J., assignor to Diamond Paper & Box Company, Philadelphia, Pa., a corporation of Pennsylvania

Application September 19, 1950, Serial No. 185,541

3 Claims. (Cl. 229—52)

In the merchandising of various items, it is frequently desirable to provide a single compact package containing a predeterminedly fixed number of the item, as, for example, in the merchandising of canned beer or other product in connection with which it is desirable to provide a readily transportable package containing say six cans of the product.

The present invention relates generally to and has among its objects the design and construction of a cardboard box which may be readily filled with the desired number of cans and effectively sealed to provide a sealed package which, while the outer surfaces thereof are all substantially flat and free of such external projections as might interfere with convenient stacking of a number of the boxes one upon the other during their transportation and while they are in storage, is nevertheless provided with a readily available hand-hold for easy carrying of the individual package by the purchaser thereof.

A further and important object of the present invention is to provide a simple, rugged and inexpensive construction of box of the character aforesaid having top closure flaps with built-in hand-hold elements of such design and construction as to facilitate effective sealing of the closure flaps through the use of automatic box-flap sealing apparatus, the hand-hold elements being normally contained in the flat plane of the sealed closure flaps until such time as they may be required for carrying purposes and being adapted to be swung out of said plane into handle-forming position.

Other objects and advantages of the invention will be apparent more fully hereinafter; it being understood that the present invention consists in the combination, construction, location and relative arrangement of parts, all as described more fully hereinafter, as shown in the accompanying drawings and as finally pointed out in the appended claims.

In the accompanying drawings, which are illustrative of a preferred embodiment of the invention,

Figure 1 is a perspective view showing the box in its filled condition just prior to final sealing of its top closure flaps;

Figure 2 is a perspective view showing the top portion of the box as it appears when finally sealed;

Figure 3 is a perspective view similar to Figure 2 but showing the hand-hold elements raised into handle-forming position;

Figure 4 is a transverse sectional view as taken along the line 4—4 of Figure 2;

Figure 5 is a transverse sectional view as taken along the line 5—5 of Figure 3; and

Figure 6 is a plan view of the single blank of cardboard or other sheet material of which the box is formed.

The essential feature of the present invention is best illustrated in Figures 2 and 3. The face viewable in Figures 2 and 3 is the top of the box as shown in Figure 2, this top of the box being substantially flat so as to facilitate stacking of a number of the boxes one upon the other. The distortion which is shown in Figure 2 is substantially exaggerated when compared with that existing in the actual construction of the box, the distortion being resorted to for better illustration of the box construction. In this connection it will be noted that while the sealed flat top of the box includes therein the handle-forming elements referred to more specifically hereinafter, these elements are of such construction and relative arrangement that when disposed flatwise in the plane of the box top they form no such external pro-

2

jections as might interfere with vertical stacking of the filled and sealed boxes.

Moreover, it is important to note that the handle-forming elements are so incorporated in the top closure flaps of the box as coplanar elements of said flaps that sealing of the flaps in their superimposed relation shown in Figures 2 and 5 is readily effected through the use of any suitable flap-sealing apparatus, either manually or automatically operated. Of course, such apparatus forms no part of the present invention and is accordingly neither shown nor described herein.

The box of the present invention is made of a single blank of suitable sheet material as shown in Figure 6 of the drawings. This blank is die cut and scored as shown, the score lines being indicated by broken lines and the cuts being indicated by full lines. In the blank the oblong portions 10 and 11 form the side walls of the box, while the approximately square portions 12 and 13 form the opposite end walls of the box. Integral with the lower edges of the side walls 10 and 11 are the extensions 14 and 15 which respectively constitute half-bottoms for the box, which, when the box is expanded into box form, are disposed in coplanar relation with their free edges abutting to conjointly form the full bottom of the box. The extensions 16 and 17 which are integral with the lower edges of the end walls 12 and 13 form the customary inner bottom flaps against which the half-bottoms 14 and 15 are adhesively secured.

The side wall 10 is provided with an integral extension 18 constituting a top closure flap for the box, this extension having at its outer edge a hand-hold flap 19 integral therewith. Similarly, the side wall 11 is also provided with an integral extension 20 constituting a second top closure flap which is adapted to partially overlie the closure flap 18 and form conjointly therewith a full closure for the top of the box. In addition, the top closure flap 20 is provided with a pair of laterally spaced coplanar sections 21—21 between which extends a second hand-hold flap 22, the latter being laterally defined by the slits 23—23 which separate the central hand-hold flap 22 from the laterally spaced sections 21—21. It will be noted that the slits 23—23 terminate just short of the outer edge 24 of the closure flap 20 so as to normally retain the hand-hold flap 22 in the plane of the flap 20 until such time as it is desired to raise the hand-hold flap 22 out of the plane of the flap 20 and into handle-forming position.

The hand-hold flap 22 is suitably apertured, as at 25, while the flap 19 is centrally slit to provide a hand-hold aperture for registry with the aperture 25 when the flaps 19 and 22 are superposed flatwise against one another. Preferably, the hand-hole formed in the flap 19 is provided with a reversely foldable tongue portion 26 which is adapted to be folded back as best shown in Figure 5 to provide a rounded upper edge for the hand-hole formed by the registering apertures of the superimposed flaps 19 and 22.

The side wall portion 10 is provided along its free edge with a securing flap 27 which is adapted to overlie and be secured to the vertically extending free edge of the end wall portion 13 of the blank, thereby providing an open-ended rectangular box construction having parallel end walls 12 and 13 and parallel side walls 10 and 11, the side walls being respectively provided with the top and bottom closure flaps hereinbefore described. The end walls, in addition to the bottom closure flaps 16 and 17, are respectively provided at their upper edges with top closure flaps 28 and 29, which are adapted to be folded into coplanar relation just beneath the overlapping top closure flaps 18 and 20, as is most clearly shown in Figure 1.

In the manufacture of this box the blank of Figure 6 is initially expanded into substantially rectangular condition with the overlap 27 glued or otherwise secured to the inner face of the end wall 13. The bottom closure flaps 16 and 17 are then turned and the half-bottoms 14 and 15 are then adhesively secured to these flaps 16 and 17, thereby forming a sealed bottom for the box. In this expanded condition of the box, its top is wide open and it is thus adapted to be filled with the goods which it is designed to receive, following which filling

operation the top closure flaps 28 and 29, integral with the upper edges of the end walls 12 and 13, are folded over the contents of the box. At this point the hand-hold portion 19 is turned back upon the closure flap 18 along the scored line 30 and the bottom face of said flap 18 is adhesively secured to the underlying flaps 28 and 29. The box is now in the condition shown in Figure 1 of the drawings.

Adhesive is now applied preferably to all of the bottom face of the closure flap 20 including the portions 21-21 and 22 thereof, following which the flap 20 is pressed down and secured in position against the underlying surfaces of the flaps 28 and 29 and of the flap 18, which latter surfaces also may be adhesively coated as shown in Figure 1. The structure thus obtained is best illustrated in Figures 2 and 4 wherein it will be observed that the superimposed hand-hold portions 19 and 22 are adhesively secured together as a unit which is swingable out of the plane of the box top. This hand-hold unit formed of the elements 19 and 22 adhesively secured together is normally retained flatwise in the plane of the top of the box by the readily separable connections 30-30 at the ends of the slits 23-23 which separate the hand-hold portion 22 from the laterally spaced sections 21-21 of the top closure flap 20. Upon breaking open these connections 30-30, the hand-hold unit comprising the elements 19 and 20 is free to be swung upwardly about the score line 31 into the upright carrying position shown in Figures 3 and 5, the top of the box being then maintained in its sealed condition as shown.

It will be understood, of course, that the present invention is susceptible of various changes and modifications which may be made from time to time without departing from the general principles or real spirit of the invention, and it is accordingly intended to claim the same broadly as well as specifically as indicated by the appended claims.

What is claimed as new and useful is:

1. For a fiber board box having upright walls adapted to define a rectangular opening in the top of the box, a closure for said opening comprising a pair of opposed flaps integral respectively with a pair of said upright walls and positioned over said rectangular opening, and another pair of opposed flaps integral respectively with the remaining pair of said upright walls and positioned in overlapping relation to one another and in overlying relation to said first mentioned pair of flaps, one of said overlapping flaps being provided with an integral central extension in the form of a handle-forming part folded back upon said one flap, the other of said overlapping flaps being provided with laterally spaced flap portions which flank and are detachably secured to the outer corners of a central portion in the form of a second handle-forming part, said laterally spaced flap portions being disposed in coplanar relation to said first mentioned handle-forming part, the latter being disposed in underlying relation to said second handle-forming part, said laterally spaced flap portions being adhesively secured to the underlying flap, and said handle-forming parts being adhesively secured together and swingable as a unit out of the plane of the box top into position normal to said plane after detachment of said second handle-forming part from said laterally spaced flap portions.

5

normal to said plane after detachment of said second handle-forming part from said laterally spaced flap portions, and being provided with registering apertures to form a hand-hole.

2. For a fiber board box having upright walls adapted to define a rectangular opening in the top of the box, a closure for said opening comprising a pair of opposed flaps integral respectively with a pair of said upright walls and positioned over said rectangular opening, and another pair of opposed flaps integral respectively with the remaining pair of said upright walls and positioned in overlapping relation to one another and in overlying relation to said first mentioned pair of flaps, one of said overlapping flaps being provided with an integral handle-forming part folded back upon said one flap, the other of said overlapping flaps being provided with laterally spaced flap portions which flank and are detachably secured to a central portion in the form of a second handle-forming part, said laterally spaced flap portions being adhesively secured to the underlying flap, and said handle-forming parts being adhesively secured together and swingable as a unit out of the plane of the box top into position normal to said plane after detachment of said second handle-forming part from said laterally spaced flap portions.

10

3. For a fiber board box having a rectangular opening in the top thereof, a closure for said opening comprising a pair of opposed flaps positioned over said rectangular opening, and another pair of opposed flaps positioned in overlapping relation to one another and in overlying relation to said first mentioned pair of flaps,

20

one of said overlapping flaps being provided with an integral handle-forming part folded back upon said one flap, the other of said overlapping flaps being provided with laterally spaced flap portions which flank and are detachably secured to a second handle-forming part, said laterally spaced flap portions being disposed in coplanar relation to said first mentioned handle-forming part, the latter being disposed in underlying relation to said second handle-forming part, said laterally spaced flap portions being adhesively secured to the underlying flap, and said handle-forming parts being adhesively secured together and swingable as a unit out of the plane of the box top into position normal to said plane after detachment of said second handle-forming part from said laterally spaced flap portions.

25

4. For a fiber board box having a rectangular opening in the top thereof, a closure for said opening comprising a pair of opposed flaps positioned over said rectangular opening, and another pair of opposed flaps positioned in overlapping relation to one another and in overlying relation to said first mentioned pair of flaps,

30

one of said overlapping flaps being provided with an integral handle-forming part folded back upon said one flap, the other of said overlapping flaps being provided with laterally spaced flap portions which flank and are detachably secured to a second handle-forming part, said laterally spaced flap portions being disposed in coplanar relation to said first mentioned handle-forming part, the latter being disposed in underlying relation to said second handle-forming part, said laterally spaced flap portions being adhesively secured to the underlying flap, and said handle-forming parts being adhesively secured together and swingable as a unit out of the plane of the box top into position normal to said plane after detachment of said second handle-forming part from said laterally spaced flap portions.

35

5. For a fiber board box having a rectangular opening in the top thereof, a closure for said opening comprising a pair of opposed flaps positioned over said rectangular opening, and another pair of opposed flaps positioned in overlapping relation to one another and in overlying relation to said first mentioned pair of flaps,

40

one of said overlapping flaps being provided with an integral handle-forming part folded back upon said one flap, the other of said overlapping flaps being provided with laterally spaced flap portions which flank and are detachably secured to a second handle-forming part, said laterally spaced flap portions being disposed in coplanar relation to said first mentioned handle-forming part, the latter being disposed in underlying relation to said second handle-forming part, said laterally spaced flap portions being adhesively secured to the underlying flap, and said handle-forming parts being adhesively secured together and swingable as a unit out of the plane of the box top into position normal to said plane after detachment of said second handle-forming part from said laterally spaced flap portions.

45

6. For a fiber board box having a rectangular opening in the top thereof, a closure for said opening comprising a pair of opposed flaps positioned over said rectangular opening, and another pair of opposed flaps positioned in overlapping relation to one another and in overlying relation to said first mentioned pair of flaps,

50

one of said overlapping flaps being provided with an integral handle-forming part folded back upon said one flap, the other of said overlapping flaps being provided with laterally spaced flap portions which flank and are detachably secured to a second handle-forming part, said laterally spaced flap portions being disposed in coplanar relation to said first mentioned handle-forming part, the latter being disposed in underlying relation to said second handle-forming part, said laterally spaced flap portions being adhesively secured to the underlying flap, and said handle-forming parts being adhesively secured together and swingable as a unit out of the plane of the box top into position normal to said plane after detachment of said second handle-forming part from said laterally spaced flap portions.

55

7. For a fiber board box having a rectangular opening in the top thereof, a closure for said opening comprising a pair of opposed flaps positioned over said rectangular opening, and another pair of opposed flaps positioned in overlapping relation to one another and in overlying relation to said first mentioned pair of flaps,

60

one of said overlapping flaps being provided with an integral handle-forming part folded back upon said one flap, the other of said overlapping flaps being provided with laterally spaced flap portions which flank and are detachably secured to a second handle-forming part, said laterally spaced flap portions being disposed in coplanar relation to said first mentioned handle-forming part, the latter being disposed in underlying relation to said second handle-forming part, said laterally spaced flap portions being adhesively secured to the underlying flap, and said handle-forming parts being adhesively secured together and swingable as a unit out of the plane of the box top into position normal to said plane after detachment of said second handle-forming part from said laterally spaced flap portions.
